[57] CLAIM

The ornamental design for a mobile terminal, as shown and described.

DESCRIPTION

FIG. 1 is a perspective view of the mobile terminal of the invention;

FIG. 2 is a top plan view thereof;

FIG. 3 is bottom plan view thereof;

FIG. 4 is a right side elevational view thereof, the left side being a mirror image thereof;

FIG. 5 is a rear end elevational view thereof; and,

FIG. 6 is a front elevational view thereof.

The cord has been shown broken away in the views to indicate an indeterminate length.
